SHOE POLISHING MACHINE

Joseph Wheeler, Kecoughtan, Va., assignor of
one-tenth to Harry Fleming, Kecoughtan, Va.,
and thirty-five per cent to Daniel L. Holden,
Washington, D. C.

Application August 19, 1937, Serial No. 159,960

5 Claims. (Cl. 15—97)

This invention relates to a shoe polishing machine.

It aims to provide a novel structure driven by a suitable motor and having a polishing element or elements adapted to travel in a path approximating the contour of an engaged portion of a shoe or shoes.

It is also an object to provide a portable structure and one having a novel polishing element and mounting therefor, the element being an endless band, interengaged at its edges with a mounting frame.

The more specific objects and advantages will become apparent from a consideration of the 15 description following taken in connection with accompanying drawings illustrating an operative embodiment.

In said drawings:

Figure 1 is a view in side elevation of the machine;

Figure 2 is a vertical sectional view taken on the plane of line 2—2 of Figure 1;

Figure 3 is an enlarged side elevation of the cleaning element and taken on an enlarged scale;

Figure 4 is a vertical section taken on the line 4—4 of Figure 3;

Figure 5 is a cross section taken on the line 5—5 of Figure 4;

Figure 6 is a detail section taken on the line 6—6 of Figure 3;

Figure 7 is a detail plan view of the polishing element, being fragmentary, and looking from the inner surface;

Figure 8 is a detail section taken on the line 8—8 of Figure 2;

Figure 9 is a section similar to Figure 8 taken through a modified form;

Figure 10 is a fragmentary section taken on the same plane of Figure 2 but through a modified form;

Figure 11 is a detail section taken on the line 11—11 of Figure 10;

Figure 12 is a side elevation of a modified form 45 of the machine;

Figure 13 is a detail section taken on the plane of line 13—13 of Figure 12;

Figure 14 is a plan view of the modified form; and

Figure 15 is a fragmentary end elevation of the modified form taken from the side opposite to that of Figure 12.

Referring specifically to the drawings and first to the form of the invention disclosed in Figures 1 to 11, the structure disclosed is portable and

may be used as shown or mounted in any suitable way as in a casing or cabinet, connected to a floor or other support, and the like.

An electric motor or the equivalent is shown at 10 constructed or geared to operate a plurality 5 of shafts or spindles 11. The central shaft is usually positively driven from the motor and it has a pinion 12 thereon and pinions 13 on the other shafts or spindles mesh with each other and with the pinion 12 whereby all are rotated. 10 The shafts are journaled in a bearing bar 14 suitably fastened to the frame of the motor. From this unit having the plurality of driven spindles or shafts 11, one or more polishing devices such as at 15 are driven, one polishing device 15 being driven by each shaft or spindle 11, through the medium of a flexible shaft 16 having a clutch tube 16a at one end adapted to detachably slip over and frictionally or otherwise engage an adjacent shaft 11. 20

The polishing element 15 has an arch shaped frame 15a as best shown in Figure 4. Such frame is of skeleton form, being made for instance of metallic wire and the same is rigid. Traversing the frame, is an endless belt 17. 25

Said belt may be made of any flexible or suitable material, for instance leather, textile fabric or the like and along longitudinal edges is supplemented by laminations 18 which are stitched in place at 19 or otherwise fastened. Such laminations provide grooves 20 at the outer edges of the belt. Said grooves 20 receive rails or bars 21 and 22 of the frame 15a, which are of the shape of the path which belt 17 follows or travels in. Since the belt 17 is flexible, said grooves 30 20 and rails or bars 21 are readily interengaged. Thus mounted, the endless belt will travel in an endless path substantially following the margin of the frame 15a. 35

The belt may be of the cross section disclosed 40 in Figure 8 but it is preferred to reinforce the laminations 18 in particular, and the adjacent portions of the belt proper by means of U-shaped metallic staples 24, arranged at suitable intervals, as disclosed in Figures 7 and 9. This construction stiffens the belt to avoid any tendency toward detachment of the belt from the rails or bars 21. Reinforcing rods 23 may also be fastened across the inner surface of belt proper 17, if desired. 45

Any suitable form of polishing surface may 50 be employed. To this end, a soft polishing element 25 may be used consisting for instance of an outer sheet 26 of textile fabric or of leather, with a filling 27 therebeneath, of leather, textile material or the like. 55

In lieu of the polishing element or surface 26, I may use a suitable brush construction as in Figures 10 and 11 where tufts of bristles 28 are carried by a flexible backing member 29, in turn fastened to the endless belt here designated 17. 5

Suitably fastened to the frame 15a is an open handle 30 and adjacent each end of the frame, a shaft 31 is journaled in bearing portions 32 provided on the frame. Such shafts 31 each have 10 a pair of sprocket wheels 32 keyed thereto and the sprocket wheels are adapted to engage recesses or eyelets 33 provided in the inner surface of the belt proper 17. One of the shafts 31 is extended and a coupling 34 carried by the flexible 15 shaft 16 is detachably connected therewith. 15

As a result of the construction described, after blacking or other polishing material is applied to the shoe, the motor 10 is operated under any conventional control, causing the flexible shaft 20 16 to be driven from one of the shafts or spindles 11, thereby rotating one of the shafts 31 and causing the sprockets 32 to move the belt 17 in an endless path, following the general shape of frame 15a. The shoe is placed within the frame or arch and the polishing element engages the blacking or polishing material and very effectively shines the same and completes the polishing of the shoe, the shoe being manipulated from time to time to place various portions thereof in contact with the moving polishing element. 30

A modified form of the invention is shown in Figures 12 to 15. In this form, the tip of the shoe and the heel may simultaneously be polished or a pair of shoes may simultaneously be polished, while the user is seated. This form of the invention uses four of the polishing elements 15', which are identical in construction with the polishing elements 15. Two of such polishing elements are arranged vertically and two 40 are arranged horizontally so that the shoes may simultaneously be engaged by a vertically arranged one and a horizontally arranged one. A motor 10' similar to that at 10 is used and in this instance it may have rollers or casters 34a 45 arranged to engage the floor so that it may be more readily transported. A mounting frame is provided at 35, being attached to the casing of the motor 10'. This frame has sections 36 on opposite sides of the motor which mount the vertically disposed cleaning elements 15' so that they may be adjusted toward and away from each other. To this end, arms 37 extend from the sections 36 and overlap each other, having various openings 38 therethrough adapted to 50 aline at different adjustments and to have bolts 39 detachably passed therethrough to secure them in different adjusted positions. The driving shafts for the vertically disposed cleaning elements 15' are here designated 31'. Said shafts 55 are driven by flexible shafts 40 from elected shafts or spindles 11' like those at 11. The bearings for the shafts 40 are provided as at 41 mounted in bifurcations 42 of portions of sections 36 of frame 35. Couplings 43 connect the flexible shafts 40 and shafts 31'. 60

The frame 35 has rigid upwardly deflected bars or arms 44 connected to the frame 15a of the horizontal polishing devices 15' and they mount bearings 45 in combination with bifurcations 46 70 of connecting arms 47. In the bearings 45, shafts 31a are journaled which are driven by flexible shafts 48 from suitable spindles 11'. Shafts 31a correspond to similar shafts 31 of the first form of the invention and the shafts 31'. The frames 75 of the horizontal polishing elements are con-

nected by a bar or auxiliary framework 50 which is adapted to be pulled or urged toward a support by a contractile coil spring 51 connected at 52 to the auxiliary frame and at 53 to the support. A handle or the like 54 may have diverging portions 55 connected to the auxiliary frame 50, so as to draw the horizontal polishing devices against the tension of the spring 51 into intimate contact with the shoe or shoes being polished. 10

The frame 35 has uprights 57 joined by a crossbar 58 from which coil springs 59 depend and resiliently support and are connected to the supporting frame means for the vertical polishing devices 15'. Such devices may be depressed against the tension of the springs, through engagement with the handles 30' to better engage and polish the shoes. 15

It will be realized that with the motor 10' operating, the vertical and horizontal polishing devices 15' will be operated and that the polishing elements thereof will simultaneously polish the tips of shoes and the heels of shoes, the same being operable to effectively engage the shoes since they are adjustably and resiliently mounted under control of the springs 51 and 59. Major adjustments may be effected through the openings 38 and bolt 39 and similar openings 60 and a bolt 61, co-acting with overlapping sections forming the rod or frame part 50. 30

Various changes may be resorted to provided they fall within the spirit and scope of the invention.

I claim as my invention:

1. Apparatus of the class described comprising a frame of arch shape, an endless belt removably interengaged at opposite side edges with the frame and operable to follow its contour, said belt being relatively stiff to prevent accidental detachment, a polishing element carried by the belt, and means to drive the belt. 40

2. Apparatus of the class described comprising a frame, an endless belt removably interengaged with the frame and operable to follow its contour, said belt being relatively stiff to prevent accidental detachment, a polishing element carried by the belt, means to drive the belt, spaced bars on the frame, said belt having grooves engaging said bars and locating the belt between them. 45

3. Apparatus of the class described comprising a frame, an endless belt removably interengaged with the frame and operable to follow its contour, said belt being relatively stiff to prevent accidental detachment, a polishing element carried by the belt, means to drive the belt, spaced bars on the frame, said belt being laminated with the laminations so arranged as to provide grooves in the side edges of the belt, said grooves being arranged to engage said bars with the belt between the latter. 55

4. Apparatus of the class described comprising a frame, an endless belt removably interengaged with the frame and operable to follow its contour, said belt being relatively stiff to prevent accidental detachment, a polishing element carried by the belt, means to drive the belt, spaced bars on the frame, said belt being laminated with the laminations so arranged as to provide grooves in the side edges of the belt, 70 said grooves being arranged to engage said bars with the belt between the latter, and reinforcing elements for the laminations and adjacent portions of the band to reinforce the same against accidental detachment from the frame. 75

5. Apparatus of the class described comprising a frame, an endless belt removably interengaged with the frame and operable to follow its contour, said belt being relatively stiff to prevent accidental detachment, a polishing element carried by the belt, means to drive the belt, spaced bars on the frame, said belt being laminated with the laminations so arranged as to provide grooves in the side edges of the belt, said

grooves being arranged to engage said bars with the belt between the latter, and U-shaped reinforcing staples having their legs within the laminations and their bights passing through the adjacent portions of the band to reinforce the same against accidental detachment from the frame. 5

JOSEPH WHEELER.
